STOCKING

George J. Apar, Queens, N. Y.

Application January 11, 1955, Serial No. 33,926

Term of patent 14 years

(Cl. D47—7)

FIG. 1.

FIG. 2.

Fig. 1 is a side elevation of a stocking, showing my new design.

Fig. 2 is a fragmentary detail of Fig. 1, drawn to an enlarged scale.

The dominant feature of my design is constituted by a lace-like seam inserted in the body of said stocking and extending from the toe along the side of the foot and then up the side of the leg to the top of the stocking, the seam being connected at its side edges to the stocking by a raised welt-like connection. The opposite side of the stocking is plain.

This application is a continuation-in-part of my prior U. S. design patent application, Ser. No. D-31,300, filed July 7, 1954.

1 claim:

The ornamental design for a stocking, substantially as shown and described.
